5 Claims. (Cl. 144—279)

1

The object of the present invention is a machine for gluing together laths which are inserted into the same across the conveying direction, this machine comprising a supporting table, a conveying device for the laths and devices for gluing and pressing the laths together.

Machines of this type are known, in which the conveying device for the laths is formed as a slide running forward and backward over a table. This construction, however, is not advantageous in that the laths must be laid in front of the slide in quick succession, for the slide is continuously reciprocated and the laths are immediately pushed under the usual pressing bars. Thus, if a lath has been brought into an inexact position in front of the slide it also comes into this position under the pressing bars, so that it is impossible afterwards to put the lath into correct position with regard to the others.

Therefore, in these known machines, there is no possibility of surveying the product in manufacture, because only after the finished plate has left the machine can it be seen whether it is defectless or not. This is particularly inconvenient if defective laths (having knots, resinous pores, etc.) are used, these defects being only visible in these known machines when the laths are already glued so that they cannot be removed without stopping and returning the machine. Besides, it is often the case that a lath, in the direction of fibre, consists of several pieces between which tight butt joints should be obtained. When feeding these pieces they must be very quickly brought in front of the slide and struck against one another in their butt joints. This quick manipulation can, however, not be carried out with sufficient accuracy.

Also machines for gluing laths together are known with a supporting table consisting of a stationary plate, in which the laths are conveyed by means of drawing-in rollers. Glue is applied to the laths on inserting them into the machine and they are then gripped by the drawing-in rollers. However, correcting the position of a inexactlly inserted lath can only be carried out after having stopped and returned the machine.

In other known machines for gluing laths together the latter are conveyed by conveyer chains provided with movable drivers. However, these machines are very much complicated by the parts controlling the drivers. Besides this, it is not possible in these machines to convey laths which, in conveying direction, have together a length greater than the mutual distance of two drivers. If a certain number of laths lying one behind the

2

other do not lie on the chains in such a way that the hindmost laths bear against the drivers, the whole row of laths must be moved back by hand until the laths are gripped by the drivers. This, however, is very dangerous as the hands of the worker may easily be gripped by the conveying rollers. Besides this, on this moving back, there is a risk of the laths diverging from one another and of the butt joints between the different pieces of a lath no longer being tight. Moreover, the drivers projecting beyond the table surface constitute a danger for the worker laying the laths upon the supporting table.

The machine according to the invention remedies all the above-mentioned inconveniences. It is characterised in that the supporting table comprises conveying elements protruding only in so far above the supporting surface that between the conveying elements and the laths to be conveyed the friction necessary for conveying the latter is obtained, and that, after the supporting table, a transporting device is provided moving the laths conveyed by the conveying elements out of the plane of the latter in front of a second table on which the laths are glued together.

The accompanying drawings illustrate by way of example one embodiment of the machine according to the invention.

Figs. 1a and 1b are a plan view thereof,

Fig. 2 is a view in the direction of arrow A in Fig. 1a,

Fig. 3 is a section along the line III—III in Fig. 1b.

Fig. 4 is a partial view in the direction of arrow B in Fig. 1a.

Fig. 5 is a top view of the push beam,

Fig. 6 illustrates a part of Fig. 3, on an enlarged scale,

Fig. 7 illustrates a part of Fig. 1b, partly in section, on an enlarged scale.

The machine frame 1 carries a supporting table 3 whose supporting surface for the laths 21 is formed by bars 2. Between the latter, conveying elements in the form of bands 4 are arranged, protruding only so far above the conveying elements 4 as is required to produce the friction necessary for conveying laths.

The transport bands 4 might be replaced by conveying chains. The bands 4 run over rollers 5 mounted on the shafts 6 and 7.

The bands 4 are driven by a shaft 8 receiving its motion from a non-illustrated motor, the worm 9 and the worm wheel 10. From the chain wheel 11 mounted on the shaft 8 runs a chain 12 over the chain wheel 13 fixed to the shaft 6.

A stop 14 is provided on the upper side of the

supporting table 3. On the one end this stop 14 has a plate 15. Through a bore of this latter and the slit 16 (Fig. 2) of the carrier 17 fixed to the machine frame 1 goes the screw 18 by means of which the stop 14 is fixed. For adjusting the latter across the conveying direction the handle screw 19 is loosened so that the screw 18 can be moved along the slit 16. The position of the stop 14 is dependent on the length, i. e. on the extension of the plate to be made in the direction of fibre. This length is determined by the distance (Fig. 2) between the stop 14 and the circular saw blade 20, by means of which the assembled laths 21 are shortened to the desired length of the plate to be manufactured. The shaft 23 of the saw blade 20 is pivoted on supports 22 fixed to the machine frame 1 and is driven by the pulley 24.

In order to guide the laths 21 which, seen in Fig. 3, are moved by the conveying bands 4 from the left to the right, a beam 25 fixed to the bolt 26 is provided. This beam 25 must be adjustable in the vertical direction in accordance with the thickness of the laths 21 to be assembled. For this purpose a hand wheel 27 is provided whose shaft 28 is mounted on the frame 1 and carries a worm 29 (or a helical-toothed spur gear) engaging a toothed segment 30, the shaft 31 of which being mounted on the frame 1 by means of the bearings 32. Besides this, the shaft 31 carries two forked levers 33 reaching below the discs 34 of the bolts 26. If the beam 25 is to be adjusted in accordance with a greater thickness of the laths, the hand wheel 27 is driven in such a way that the forked levers 33, seen in Fig. 3, rotate in the clockwise direction, thereby lifting the beam 25.

For assisting the feeding operation of the bands 4 a roller 35 acting upon the upper side of the laths 21 is provided. The pivots 36 of this roller are mounted on carriers 37 fixed to the beam 25. Therefore, if the latter is adjusted by means of the hand wheel 27, the roller 35 is simultaneously displaced accordingly. The roller 35 is driven in the following manner: The chain wheel 38 mounted on the one pivot 36 (on the right in Fig. 2) is connected by the chain 39 with the chain wheel 41 on the bolt 40. The second chain wheel 42 of this bolt 40 is connected by a chain 43 with a chain wheel 44 fixed to a shaft 6, the drive of this latter being described above. The bolt 40, besides, forms the pivot for the plates 45 and 46 which are rotatably connected with the shaft 6 and the pivot 36 respectively. Owing to the arrangement shown, the drive of the roller 35 can follow any change in the vertical position of the latter.

At the moment when the foremost lath 21 is lifted out of the plane of the supporting table 3 in a manner described later on, the laths lying on the latter must not be displaced. Any advance is then prevented by a press bar 47 arranged above the right-hand end (Fig. 3) of the table 3. This press bar 47 is pivoted on two carrying bolts 48 vertically guided by the bearings 49 of the frame 1 and loaded by springs 50 being supported on the lower bearings 49. The springs 50 tend to draw the carrying bolts 48 downwards. The left- and right-hand threaded intermediate piece 51 of the carrying bolts 48 serves the purpose of changing the length of the latter in order to adapt the vertical position of the press bar 47 to the thickness of the laths 21. The lower ends of the carrying bolts 48 are connected to levers 52 rotatable about pins 53 fixed to the frame 1. The other end of these levers 52 carries rollers

54 cooperating with cam discs 55 fixed to the shaft 8. These cam discs rotate from time to time the levers 52, seen in Fig. 3, in the anti-clockwise direction, thereby lifting the carrying bolts 48 with the press bar 47 and allowing the laths 21 on the supporting table 3 of being advanced.

10 A bracket 56 of the frame 1 carries a back wall 57; the horizontal distance between the latter and the press bar 47 can be altered in order to adjust it in accordance with the width of the laths 21. For rendering the adjustment of the back wall 57 possible, bolts 58 go through slits 59 of the horizontal flange of this back wall 57 and through the bracket 56. The back wall 57 is fastened to the bracket 56 by tightening the handle nuts 60 on the bolts 58. For adjusting the back wall 57 the handle nuts 60 are loosened.

15 Between the press bar 47 and the back wall 57 is arranged a lifting bar 61 serving the purpose of lifting the laths 21 from the supporting table 3 to the plane of the table 62 on which the gluing together of the laths takes place, glue having previously been applied to the latter in a manner described later on. The lifting bar 61 is vertically guided by the guide members 63 of the frame 1. The lifting bar 61 is carried by the plates 64 pivoted on it and to the levers 65. The latter are rotatably mounted on the frame 1 by means of the shafts 66. They carry rollers 67 cooperating with cam discs 68 on the shaft 8. In the lowermost position of the lifting bar 61 the upper edge of the same is flush with the supporting surface of the table 3, so that the foremost lath 21 can be pushed upon the lifting bar 61 by the subsequent ones. However, in the uppermost position of the lifting bar 61 the upper edge of the same is flush with the surface of the table 62 so that the lifted lath can be pushed upon the table 62 by a device described later on.

20 In Fig. 7 it is seen how the projections 69 of the lifting bar 61 enter slits 70 of the back wall 57 and cut-outs 71 of the bars 72 forming the table 62.

25 Instead of placing the table 62 above it might also be placed below the supporting table 3. Then the above described lifting device would be replaced by a lowering arrangement.

30 On the way from the supporting table 3 to the table 62 glue is applied to the laths by the following apparatus: The glue container 73 with the glue roller 74 mounted on it is fixed to the horizontal flange of the back wall 57. This glue roller 74 makes contact with the glue applying roller 75 whose pivots 76 are connected with the pivots 78 of the glue roller by means of the plates 77. The glue roller 74 is driven by the shaft 8 with the help of chain wheel 79, chain 80 and chain wheel 81. As is especially to be seen in Fig. 7, the glue applying roller 75 has grooves 82, so that the parts 83 of greater diameter only receive glue from the roller 74 and apply it to the laths. These parts 83 pass through slits 84 of the back wall 57. The flanges of the lifting bar 61, too, have cut-outs 85 within reach of the parts 83 in order to avoid that these flanges, on lifting and lowering the bar 61, are smeared with glue. By the illustrated form of the glue applying roller 75 the laths are not supplied with glue over the whole length, but only on different places. This gluing, however, is sufficient and allows of avoiding smearing of the back wall 57.

35 The laths lifted by the lifting bar 61 to the height of the plane of the table 62 are pushed 70 upon the table 62 by a push beam 86 (to the right

in Fig. 3). This push beam 86 is movably mounted on the frame 1 by means of the guides 87. A motion to and fro is imparted to the push beam 86 by levers 88 pivoted to the ears 90 of the beam 86 by means of the bolts 89. The other end of the levers 88 rotatably mounted on the frame 1 by means of the shaft 91 carries rollers 92 co-operating with the cam discs 93 attached to the shaft 8. The springs 94 provide for the rollers 92 being constantly pressed against the cam discs 93. The construction of the push beam 86 may specially be seen in Figs. 5 and 7. It has holes 95 open towards the table 62 and separated from one another by ribs 96. When the lifting bar 61 is in its uppermost position and the push beam 86, seen in Fig. 3, moves to the right, the ribs 96 go through the slits 97 of the lifting bar 61 between the bars 72, in this way, together with the transverse rib 98 (Fig. 3), pushing the lath lying on the lifting bar 61 towards the table 62.

The device for pushing laths forming the length of the plate in the direction of fibre tightly together in their butt joints may be seen in Fig. 5 wherein the push beam 86 is illustrated by a top view. The medial portion of the lever 99 is pivotedly mounted on the beam 86 and at the one end, carries a hammer 100, at the other end a pin 101. In the position shown in Fig. 5, the lever 99 is pressed by the spring 102, against the cam 103 fixed to the frame 1. The end 104 of the lever 99 lying on the side of the pin 101, in the position shown engages the pawl 105 rotatably fixed to the push beam 86 and influenced by the spring 105. The cam 103 carries a releasing pin 107 whose manner of action is described later on. By means of the member 108 a stop 109 is fixed to the push beam 86 which, after a loosening of the screw 110, can be displaced for adapting its position to the desired length of the plate to be manufactured. When the push beam 86 moves forward, i. e. in the direction of the arrow C, the pawl 105, after a certain time, strikes against the releasing pin 107 and is rotated in the anticlockwise direction, thereby releasing the lever 99. This, under the effect of the spring 102, rotates in the clockwise direction, so that the hammer 100 strikes against the foremost lath 21, whereby the hindmost lath is pressed against the stop 109 and all the laths are pushed tightly together in their butt joints 111. This done, the push beam 86 while continuing its forward motion brings the laths with their tight butt joints 111 from the lifting bar 61 to the table 62. When the push beam 86 moves back in the direction of the arrow D, the pin 101 runs upon the inclined surface 112 of the cam 103. The lever 99 is thereby returned into the position shown in Fig. 5 and is again locked by the pawl 105.

As mentioned above, the table 62, on which the laths are glued together along their longitudinal edges, is formed by the bars 72 which are supported on the back wall 57 and on the U-iron 113. Above the bars 72, bars 114 form a pressing bed. Each of the bars 114 is fixed to bolts 115, of which in Fig. 3 only one is shown for each bar 114. These bolts 115 are suspended on U-irons 116 of which only one is illustrated. Each bolt 115 carries a supporting ring 117. Between this latter and the U-iron 116 a spring 118 is inserted for each bolt 115, pressing the bar 114 belonging to it against the laths 21 on the table 62. By means of two hand wheels 119 belonging to each U-iron 116 and by means of spindles 120 engaging nuts 121 of the U-iron 113 the pressure 75

to be exerted by the pressing bed upon the laths to be glued together can be adjusted.

The width (vertical to the direction of fibre) of the plate to be manufactured can previously be adjusted on a counter. This counter counts the laths joined together in the feed direction and as the width of the laths is known, the extension of the plate vertical to the direction of fibre can be determined from the number of laths used for each plate. Seen in Fig. 2, this counter is placed on the right side of the machine. On the pin 122 fixed to the frame 1 a lever 123 is loosely mounted, on which the rod 124 is pivoted. As may particularly be seen in Fig. 4, the rod 124 is connected to a lever 126 the latter being pivoted on the frame 1 by means of the bolt 125. This lever 126 carries a roller 127 co-operating with a cam disc 128 of the shaft 8. The spring 129 fixed to the lever 123 and to the machine frame 1 presses the roller 127 continuously against the cam disc 128. On the lever 123 a driving pawl 130 is rotatably mounted, a spring 131 being fixed to this pawl and to the lever 123, which has the tendency of bringing the driving pawl 130 into engagement with the teeth of the ratchet wheel 132 loosely mounted on the pin 122. Rigidly connected with this ratchet wheel 132, but also loosely arranged on the pin 122 is the rope pulley 133 (Fig. 4) on which the rope 134 of the weight 135 is wound. Rigidly connected with the ratchet wheel 132 is the lever 136 whose one end 137 carries a pin 138 while the other end 139 of the same is determined to cooperate with lever 141 fixed to the pin 140. A pawl 143 is, pivotedly mounted on the frame 1, being under the influence of the spring 142 and serving the purpose of holding the ratchet wheel 132, against the influence of the weight 135, in that position into which it has previously been brought by the driving pawl 130. The pawl 143 can be brought out of engagement with the ratchet wheel 132 by the lever 141, and at the same time, operate the schematically illustrated apparatus 144 counting the manufactured plates. Loosely placed on the pin 122 and fixed to the frame 1 by means of the screw 145 is the lever 147 which carries the cam 146 operating the driving pawl 130 in a manner described later on. Furthermore, on the pin 122 a lever 148 is loosely mounted whose resiliently arranged bolt 149 is determined alternately to enter a space of the toothed rim 150. To this toothed rim 150 belongs a scale 151 which, together with this rim 150, is fixed to the frame 1 and has figures indicating the number of laths 21 to be joined together vertically to the direction of fibre for manufacturing one plate.

To the pin 140 of the lever 141 a further lever 152 to which a pull member 153 is connected, is fixed. Seen in Fig. 4 this member 153 runs over rollers 154, 155 to the plate 77, a spring 156 being connected to said plate 77 and to the bracket 56, thus continuously stretching the member 153. As long as lever 141 is not rotated, the arm 157 mounted on the frame 1 and influenced by a spring 158 is in the position shown in Fig. 1a. However, as soon as the lever 141 is rotated by the end 139 of the lever 136 in the anticlockwise direction, the arm 157 engages the shoulder 160 and locks the lever 141 until the arm 157 on its end 159 is rotated in the clockwise direction either by hand or automatically. As soon as the end 139 of the lever 136 rotates the lever 141 in the anticlockwise direction (seen in Fig. 1a), the pull member 153 rotates the plate 77 in the clock-

wise direction (seen in Fig. 4), thereby moving the glue applying roller 75 out of working position, so that the next lath lifted by the bar 61 is not supplied with glue and thus not glued together with the plate moving on the table 62 towards the outlet end of the machine.

The counter works as follows:

Be it supposed that the bolt 149 and with it the lever 148 is adjusted to fifty-seven laths and that the lever 136 is not in the position illustrated but in the outgoing position where the pin 138, under the influence of the weight 135 being in its lowermost position, bears against the upper edge of the lever 148. On each lath lifted by the bar 61, the shaft 3 makes one revolution. For this reason the rod 124 is lifted by the cam disc 128 once per each revolution and pulled once downward by the spring 129, the driving pawl 130 engaging the ratchet wheel 132 thereby advancing the latter by one tooth in the anticlockwise direction. This operation continues, while the weight 135 is raised, until the end 139 of lever 136 strikes against lever 141, i. e. until fifty-seven laths have been lifted by the bar 61. At this moment and as described above, the lever 141 is rotated and locked by the arm 157 and the glue applying roller 75 put out of working position. Besides this, the lever 141 disengages the pawl 143 from the ratchet wheel 132 and this, under the effect of the weight 135, commences to rotate in the clockwise direction. In the beginning it also takes along the lever 123 until the driving pawl 130 strikes against the cam 146 and, by the latter is brought out of engagement with the ratchet wheel 132. Now the latter runs back until the pin 138 strikes against the upper edge of the lever 148. Lever 148 can again be released by means of the end 159 of the arm 157 either by hand or automatically and the whole is ready for manufacturing a new plate.

If a plate, e. g. a middle layer of a plywood plate is to be manufactured with the described and illustrated machine, the worker may also place lath pieces on the table 3 which are shorter than the desired length of the plate in the direction of fibre, since tight butt joints between these pieces are guaranteed by the device shown in Fig. 5. Therefore, one may also take laths with knots, cut away these knots before bringing the laths upon the table 3 and then use these shortened pieces which are free of knots. All the laths are laid upon the table 3 side by side and one after another in the same way as they are arranged in the finished plate. As the conveying bands 4 are moved continuously, i. e. as the freshly placed laths are continuously brought into close contact with the preceding ones, one may already on the table 3 see the appearance of the finished plate. The laths are now advanced through between the bars 2 and the beam 25 which has previously been adjusted in accordance with the thickness of the laths. At the moment when the foremost lath lies upon the lifting bar 61 being in its lowermost position, the cam disc 55 presses the press bar 47 upon the next laths thereby preventing all the laths on the table 3 from being advanced. Now, the cam disc 68 raises the lifting bar 61 and during the lifting of the lath on the bar 61 one of the lath edges lying in the direction of fibre is supplied with glue by the roller 75. As soon as the bar 61 has attained its uppermost position, the cam disc 93, seen in Fig. 3, moves the push beam 86 to the right and this latter pushes the lath lying on the lifting bar 61 between the table 62 and the pressing bed formed by the bars 114. 75 mounted on said member, and a striking device

Hereupon, push beam 86 and lifting bar 61 are returned. If the latter is again in its lowermost position, the press bar 47 is lifted; the bands 4 move the next lath upon the bar 61, the above-mentioned cycle begins anew and the second lath on the table 62 is brought into contact with the former lath and, on moving forward together, the second lath is glued to the former one. This cycle is repeated until the counter, in a manner described above, brings the glue applying roller 75 out of working position. The plate is finished.

What I claim is:

1. In a machine for gluing together laths, a supporting table for the laths, conveying elements for yieldably advancing the laths on said supporting table, a second table for gluing the laths together, lying out of the plane of said supporting table, a back wall adjustable in the direction of movement of said conveying elements, a transporting device between said supporting table and said back wall, for moving the laths conveyed by said conveying elements to a position at the front of said second table, means for moving the laths from the transporting device on to the second table, and a glue applying device on said back wall for supplying the laths with glue during movement of said laths by said transporting device.
2. In a machine for gluing together laths, a supporting table for the laths, conveying elements for yieldably advancing the laths on said supporting table, a second table for gluing the laths together, lying out of the plane of said supporting table, a pressing bed for pressing the laths against said second table, a back wall adjustable in the direction of movement of said conveying elements, a transporting device between said supporting table and said back wall, for shifting the laths conveyed by said conveying elements to a position at the front of said second table, a glue applying device on said back wall for supplying the laths with glue during their movement by said transporting device, and a reciprocatingly driven push member for moving the shifted laths between said second table and said pressing bed.
3. In a machine for gluing together laths, a supporting table for the laths, conveying elements for advancing the laths on said supporting table, a second table for gluing the laths together, lying out of the plane of said supporting table, a back wall adjustable in the direction of movement of said conveying elements, said back wall having slits, a transporting device between said supporting table and said back wall, for moving the laths conveyed by said conveying elements in front of said second table, means for moving the laths from the transporting device on to the second table, and a glue applying device on said back wall, comprising a glue applying roller projecting through said slits into the path of the laths moved by said transporting device.
4. In a machine for gluing together laths, a supporting table for the laths, conveying elements for advancing the laths on said supporting table, a second table for gluing the laths together, lying out of the plane of said supporting table, a back wall adjustable in the direction of movement of said conveying elements, a transporting device between said supporting table and said back wall, for moving the laths conveyed by said conveying elements in front of said second table, a device on said back wall for applying glue to the laths, a member for moving the laths from said transporting device onto said second table, stop means mounted on said member, and a striking device

on said member for pushing the laths against said stop means in a direction substantially perpendicular to the direction substantially perpendicular to the direction of advance by said conveying elements.

5. In a machine for gluing together laths, a supporting table for the laths, conveying elements for advancing the laths on said supporting table, a second table for gluing the laths together, lying out of the plane of said supporting table, a back wall adjustable in the direction of movement of said conveying elements, a transporting device between said supporting table and

said back wall, for shifting the laths conveyed by said conveying elements in front of said second table, means on said back wall for applying glue to the laths, a reciprocatingly driven push mem-

ber for moving the shifted laths along the second table, stop means on said push member, and a striking mechanism on the front side of said push member, for pushing the laths against said stop means in a direction substantially perpendicular to the reciprocating movement of said push member.

GOTTFRIED MAURER.
